UNITED STATES PATENT OFFICE.

JAMES A. BUTLER, OF WOLLASTON, MASSACHUSETTS, ASSIGNOR, BY MESNE ASSIGNMENTS, TO AMERICAN FELT COMPANY, A CORPORATION OF MASSACHUSETTS.

LAP COUNTER OR INDICATOR.

1,287,872.

Specification of Letters Patent. Patented Dec. 17, 1918.

Application filed April 26, 1916. Serial No. 93,792.

To all whom it may concern:

Be it known that I, JAMES A. BUTLER, a citizen of the United States, residing at Wollaston, in the county of Norfolk and State 5 of Massachusetts, have invented new and useful Improvements in Lap Counters or Indicators, of which the following is a specification, reference being had to the accompanying drawings, forming part thereof.

10 This invention has reference to improvements in devices for counting the laps in the formation of a bat or for indicating the presence or approach of a point on material of which notification is desired. In its application, as herein more particularly referred to, the invention relates to a device adapted to count and indicate the laps of felt taken up successively in superposed relation on the carrier or apron of any known 15 bat forming machine whereby at or about the completion of the application of the final lap attention may be called to the fact.

An object of this invention is to so construct a lap counting device that the application 20 of the successive laps may be indicated and that at or about the completion of the application of a predetermined number of laps, to the bat under process of formation, an alarm may be sounded.

30 Another object of the invention is to provide means for automatically resetting the device.

Other objects of the invention will appear from the following description.

35 The invention consists in the novel means for intermittently operating the indicator device and in the mechanism for preventing the effective operation of said means at times.

40 The invention also consists in the means for resetting the mechanism relative to its indicating elements.

The invention also consists in the means for alarming the operator.

45 The invention also consists in such other novel features of construction and combination of parts as shall hereinafter be more fully described and pointed out in the claims.

50 Figure 1, represents a front elevation of the improved lap counter shown in relation to parts of a bat forming machine of well known construction.

Fig. 2, represents an end view of the im-

proved device, a part of the bat carrying 55 apron being shown in section.

Fig. 3, represents a rear view of parts of the device portions of the same being broken away.

Fig. 4, represents a sectional view taken 60 on line 4—4 Fig. 3.

Fig. 5, represents enlarged details of some of the parts.

Similar characters of reference designate 65 corresponding parts throughout.

The improved lap counter is herein illustrated in relation to a bat forming machine of any ordinary construction having a continuous lap carrier or apron mounted or sustained by rolls or other suitable means 70 and operated in any usual manner to take up, usually from a preliminary machine, a lap of felt and to carry said lap around to take up other similar laps in superposed relation until the product constitutes a bat of 75 the desired thickness or having the desired number of laps, as the case may be. Such machine usually has a side frame of which a portion is shown at A and is provided with the carrier or apron B adapted to be 80 sustained and operated in any known manner and preferably having the reinforced edge C. In the present instance this apron B is provided with the raised member D the purpose of which will hereinafter be de- 85 scribed.

Mounted on the frame member A is the base 5 of the bracket 6 having the plate 7. Bracket 6 has the upwardly extending member 8, the laterally extending arms 9 and 10, 90 and the bracket member 8 has the studs 11, 12 and 13, on the latter of which studs 12 and 13 is secured the dial 14 which has suitable graduations on its face.

Bracket member 6 has, in alinement with 95 the axis of dial 14, a bearing in which is journaled the shaft 15 which extends through an opening in the dial 14 and has at its outer end the pointer or hand 16 adapted, when shaft 15 is rotated, to swing 100 over the face of said dial.

On said shaft 15 is fixed the pulley sheave 17 having fixed thereto the cable 18 which extends through a bore in the bracket 6 and the frame A and has a suitable weight 19. 105 The ratchet 20 is also fixed on said shaft 15 and has a series of transverse perforations to receive pins 21 and 22. The actuation of

shaft 15 and the mechanism in one direction will be effected by the weight 19 through its cable 18 and sheave 17 while the intermittent operation of said shaft 15, and of course 5 its pointer 16, against said weight 19 will be effected by the pawl 23 pivotally mounted on a member of the pawl arm 24 and pressed by its spring 25 into engagement with the teeth of ratchet 20. This pawl arm 24 is mounted 10 to swing on shaft 15 and has the pivoted connecting rod 26 which at its lower end extends through a perforation of the arm 27 which arm 27 is located between the stop 28 of said rod 26 and the collar 29 which is 15 slideable on said rod and is sustained by the spring 30 whereby the action of said arm 27 on rod 26 is cushioned in one direction.

Arm 27 constitutes a member of an actuator device which comprises the shaft 31 20 mounted to rock in a bearing of the bracket 6 and having the lever 32 furnished with the rider disk or wheel 33, spring 34 acting against arm 27 tends to swing upward said arm and rod 26, and to effect the rocking of shaft 31 to swing downward the free end of lever 32 to press its rider 33 against the surface of the carrier apron C in line with the projection or rise D on said carrier apron and, in its passage beneath the rider 33 the 30 carrier apron is sustained by the member 35 which is sustained by the arm 36 secured to the bracket plate 7. (Fig. 2.)

Provision is made to prevent the retractive rotation of ratchet 20 with the retraction of pawl arm 24, under certain conditions, by providing the bracket arm 10 with the pivoted pawl 37 which is pressed by its spring 38 in a direction to engage the teeth of the ratchet 20 and to hold said ratchet 40 during the retractive movement of pawl arm 24 and its pawl 23 effected by the action of spring 34 on the arm 27 and the transmission of motion from said arm 27 through stop 28 and rod 26 to said pawl carrying 45 arm 24.

The journaled portion of shaft 15 is embraced by the sleeve 39 and on this sleeve is mounted, to swing, the member 40 having the angularly positioned arms 41, 42 and 43 50 of which arm 41 has the projection 44 and is of a length and construction to be yieldingly engaged at its upper end by a coöperating spring 45 mounted at the upper end of the bracket 8, said arm 41 having a limited 55 movement between stops at this portion of said bracket 8; arm 42 is of a length to extend approximately to the periphery of ratchet 20 having a limited movement between stops of arm 10 and arm 42 has the shield 46 which overlies said periphery and by a movement of member 40 may be introduced between said periphery of ratchet 20 60 and the pawls 23 and 37 whereby said pawls may be held from engagement with the teeth 65 of said ratchet to permit weight 19 to act in

effecting a retractive rotation or resetting of the sheave 18 and the parts fixedly mounted on the shaft 15 including the ratchet 20; arm 43 of said member 40 has the cam edge 47 and is adapted to be intercepted by the 70 stop 11 of bracket member 8, the edge 47 co-operating with the cam finger 49 of the latch or hook 50 which is pivotally mounted on the bracket member 8 and has the spring 51 which acts to draw downward the free end 75 of said latch.

Pivotally mounted on the arm 9 of bracket 8 is the alarm carrier 52 having the projection 53 adapted to be engaged by the latch 50 to sustain said carrier 52 in the position shown in Figs. 1 and 2 under certain conditions. On the extension 54 of this carrier 52 is the alarm gong 55 having a striking device or hammer of any usual construction adapted to be operated by or through the 85 rod 56 which rod is adapted to be actuated by its bell crank lever 57 pivotally mounted on a stud extending from the carrier 52 and having one of its arms furnished with the cam edge 58. In order, at times, to effect 90 the intermittent actuation of bell crank lever 57 I provide the shaft 59 which is journaled in a bearing of carrier 52 and has at one end the wheel 60, adapted to be driven by contact with moving material, and at the other 95 end with the disk 61 having the tooth 62 which in the rotation of said disk 61 is adapted to ride against the cam edge 58 of the lever 57 to effect the swinging of said lever to operate the gong or alarm striker. 100

The pins 21 and 22 may be placed in various perforations of the ratchet disk 20 to effect a controlling action on parts of the mechanism as will hereafter be described. Ordinarily pin 22 will be placed relative 105 to the location of pointer 16 and pin 21 will be placed in a perforation of said ratchet disk 20 corresponding to the number of laps of material to be laid or to the predetermined number of intermittent actuations of the 110 ratchet disk desired to be accomplished prior to the release of the alarm carrier or the bringing of the alarm apparatus into action. It is to be understood that these pins 21 and 22 extend sufficiently from one surface of 115 the ratchet disk 20 to, at times, engage the projection 44 on arm 41 of the controller member as indicated in Fig. 2 of the drawings.

With the parts of the machine positioned 120 approximately as shown in the drawings it will be seen that at each movement of the projection D beneath its related rider disk 33 said disk will be raised or will ride upward thus effecting the swinging movement 125 of lever 32 to draw down rod 26 whereby the pawl arm 24 will be swung a limited distance and the pawl 23 of said arm 24 will act in engagement with a tooth of ratchet disk 20 to partially rotate said disk 20, the shaft 130

to which said disk is fixed, the sheave 17 to take up cable 18 against the action of weight 19 and to swing the pointer 16 relative to dial 14 whereby to indicate such movement.

5 As the pawl arm 24 with the mechanism actuated through it reaches the limit of such movement the holding pawl 37 becomes engaged with the ratchet disk 20 and holds the same against retractive movement exerted 10 by the weighted cable 18 while pawl arm 24 is returned to place by the swinging of lever 32 under the action of spring 34.

After a predetermined number of actuations of the ratchet disk 20 has been accomplished by an equivalent number of movements of the projection D beneath the rider 33, said operations being indicated by the pointer 16 on the dial 14, pin 21 will engage the projection 44 on arm 41 of member 40 15 and, on the next actuation of ratchet 20 will effect the swinging of said arm 41 and its related arms 42 and 43 with the result that said arm 41 will be brought into engagement with spring 45 which will resist the retractive movement of said arm 41; arm 42 will carry its shield 46 between the pawls 23 and 37 and the teeth of ratchet disk 20 and the edge of said shield riding against the curved edges of said pawls may effect the swinging 20 of said pawls out of engagement with said ratchet, simultaneously arm 43 of member 40 acts by its edge 47 against member 49 of latch 50 to swing said latch out of engagement with the projection 53 of carrier 52 25 whereby said carrier may swing downward until its traveler disk 60 rides on the apron B or on material carried by said apron and is rotated by frictional contact with such apron or material whereby the projection 40 30 of the disk 61 is caused to actuate lever 57 to operate the alarm and to thus notify the operator that this particular machine requires attention.

At the time at which the pawls 23 and 37 45 are both disengaged from ratchet 20 said ratchet with its shaft 15 and sheave 17 may be reversely rotated by the cable 18 of said sheave 17 under the drawing action of weight 19 and pointer 16 will swing with shaft 15 to its initial position. In such retractive rotation of ratchet 20 and as the pointer approaches its initial position pin 22 engages the projection 44 of arm 41 and carries said arm out of engagement with spring 50 55 while the rotation of member 40 caused by the swinging of arm 41 acts to swing arm 42 to move its shield 46 from between the pawls 24 and 37 and ratchet 20.

Such resetting action of the indicating 60 and alarm releasing mechanism is independent of the alarm mechanism and this latter mechanism can continue to operate after such resetting has occurred and until the carrier 52 is swung upward to engage its 65 projection 53 with the latch 50, this may be

accomplished by the operator at the time he removes the laps of material from the apron B.

Having thus described my invention I claim as new and desire to secure by Letters 70 Patent:

1. Mechanism of the nature described comprising a traveling member having a cam, an alarm carrier mounted to move toward said traveling member, alarm mechanism mounted on said carrier and having an actuating device operative through traveling contact of said member, a latch adapted to sustain said alarm carrier, and latch releasing means having an actuating device 75 adapted to be intermittently operated by said cam of the traveling member to progressively advance said latch releasing means toward the latch releasing point.

2. Mechanism of the nature described, 85 having, in combination, a traveling member for conveying a strip of felt or other material, a cam carried by the traveling member, an element in the path of the travel of the cam, an indicating device connected to said 90 element to progressively indicate the intermittent engagement of the cam with said element, means for resetting the indicating device, means for sustaining the indicating device from resetting movement, and means 95 actuated by engagement of the cam with said element to release said sustaining means.

3. Mechanism of the nature described comprising a traveling member having a 100 cam, a bracket adjacent said member and having a pivoted arm, an alarm carried by said arm and having an actuating device adapted to be operated by traveling contact of said member, a latch pivotally mounted on 105 said bracket and adapted to engage and sustain said arm, means to release said latch, and means for operating said release means including an element adapted to be actuated by the cam of said traveling member. 110

4. Mechanism of the nature described comprising a traveling member having a cam, a bracket adjacent said member and having a pivoted arm, an alarm carried by said arm and having an actuating device 115 adapted to be operated by traveling contact of said member, a latch pivotally mounted on said bracket and adapted to engage and sustain said arm, means to release said latch comprising a rotary shaft having a ratchet, 120 a pawl to engage said ratchet, and means adapted to be actuated by the cam of said traveling member to intermittently move said pawl in an advancing direction.

5. Mechanism of the nature described, 125 having, in combination, a traveling member for conveying a strip of felt or other material, a cam carried by the traveling member, a shaft, a ratchet mounted on the shaft, a pivoted arm having a pawl to engage the 130

ratchet, an actuator for the pivoted arm intermittently operated by said cam to effect the intermittent rotation of the shaft through said pawl and ratchet wheel, an indicating device operated by rotation of said shaft, a pivoted arm having a shield adapted to be interposed between the ratchet and pawl, and means actuated by movement of said shaft to move said shield arm to 10 interpose its shield between the ratchet and pawl.

6. Mechanism of the nature described, having, in combination, a traveling member for conveying a strip of felt or other material, a cam carried by the traveling member, an element in the path of the travel of the cam, an indicating device connected to

said element to progressively indicate the intermittent engagement of the cam with said element, an alarm mechanism operated by engagement of a member thereof with the traveling member, a latch member for normally sustaining said alarm mechanism out of operative engagement with the traveling member, means actuated by movement 25 of said element for releasing the latch member to permit operative engagement of the alarm mechanism with the traveling member, said alarm mechanism constructed to be returned to inoperative position by the 30 engagement of the cam with said member of the alarm mechanism.

JAMES A. BUTLER.
